UNITED STATES PATENT OFFICE

JOHN R. SMITH, OF LOS ANGELES, CALIFORNIA

WATER-TRAP AIR-ELIMINATING CLOSET BOX

Application filed February 25, 1930. Serial No. 431,142.

This invention relates to water closets and more especially to closets having bowls provided with siphon jet passages.

My present invention is an advance of the art as shown in my prior patents in this class, and over my several pending applications as follows; S. N. 419,033, filed Jan. 7, 1930, and S. N. 417,095, filed Dec. 28, 1929.

It is my aim to accelerate the discharge of bowl contents with the least possible increment of air discharge into the bowl from the supply system of flushing water, and, to the greatest extent possible, avoid displacement of air outward from the top of the bowl. This will be accomplished if there is no rise of water in the bowl as a result of flushing and if there is no air discharged from the system to the bowl.

Therefore, the invention consists of means to effect discharge of the basin without rise of water, at least until after eduction by siphon has occurred, and provision of means and such a system of connection as will reduce air capacity of the line of flow to the jet intake of the bowl to the least possible, practicable minimum.

The principle involved is to provide a flow line as free of air capacity as possible thus eliminating air discharge to the bowl and to provide a nozzle or port whose discharge is coaxial with the intake end of the jet passage so that the kinetic energy and velocity factors in the flush flow will be combined to act as a ram on the standing water in the passage and so most forcibly impinge this toward the siphon leg of the bowl.

It will be understood that the means to achieve the desirable functions may be incorporated integrally in the bowl body or may be attached elements of appropriate structure.

The invention consists in certain advancements in this art as set forth in the ensuing disclosure and having, with the above, additional objects and advantages, and whose construction, combination and details of means, and the manner of operation will be made manifest in the description of the hereinafter illustrative embodiment; it being understood that modifications, variations and

adaptations may be resorted to within the scope, principle and spirit of the invention as it is more directly claimed hereinafter.

Figure 1 is a vertical, sectional view of one type of installation and bowl combination. 55

Figure 2 is an outer end view of one form of trap and space eliminator, and

Figure 3 is a side elevation and partial sectional view thereof.

Figure 4 is an inner end view of the eliminator. 60

Figure 5 is a plan of a close-hitched, flush-valve assembly, and

Figure 6 is a side elevation of the hitch connection. 65

A closet bowl 2 is shown as provided with a jet passage 3 discharging at 4 toward leg of a siphon chamber, in the usual well known manner.

Ordinarily the intake end 7 of the passage 3 opens into a box 8 which has openings to the flush rim 9 for washing down the bowl. By my present invention this wash down is delayed until after the basin contents have been siphoned off. 70

Any suitable flushing water supply means may be combined with the bowl. Fig. 1 shows a flush pipe 11 appropriately connected to the bowl box 8. In order to reduce the air volume as much as possible in advance of the mouth 7 of the jet passage a water trap is interposed in the flow line to the passage; the water X held in the trap displacing an equal volume of air which otherwise would be projected with the flush water to the bowl ducts 3-9 80 and so be dispelled upward with contaminated air in the bowl. Air carried through the passage 3 will bubble up into the bowl basin water and pass thence from the bowl and my object is to reduce all air possible as by a trap in the line to the passage 3 and in advance of its mouth 7, or by a close connection, or hitch, of a flush valve 20, Fig. 6. 85

The trap includes, in one form, a closed shell 17 discharge from which is through a back-up pipe 18 whose intake mouth determines the level of trapped water in the trap space; the discharge end of this trap 18 being disposed co-axially with the mouth 7 of the passage 3 so that the stream of flush water 100

from the trap is directed straight into said mouth and impinges with high velocity and energy on the standing water in the foot of the passage with the result that this is driven 5 rapidly to the siphon leg and the eduction of basin contents is started without rise of liquid in the basin, such rise being objectionable because of upward displacement of air from the bowl. Thus the trap has dual functions: air displacement and directed line of 10 flow of flush water to the jet passage.

The discharge pipe 18, of the trap, will have its outlet 19 disposed in definite relation to the respective jet passage mouth 7, and 15 one arrangement is shown in dotted lines 18', Fig. 3, for horizontal discharge. In Fig. 4, divergent outlets 18^a are shown in dotted lines, as for certain types of bowls.

It will be seen that water will back up in 20 the box 8 and flow to the flush rim 9, following the initiated bowl siphoning action; the outlet 19 of the trap being made larger than the outlet of passage 3 so as to provide rim flush supply.

25 For ready adaptation the shell 17 is shown as having a threaded nipple 17^a of conventional form with a gasket assembly 17^b to seal it in the juncture box 8; the shell providing the trap and resembling a plug substantially 30 filling the box chamber.

In Figs. 5 and 6 a flush valve 20 is shown as close-connected or hitched at 21 to the box 8 and thereby eliminates air space incident to a long connection, as wholly the practice up to 35 the time of this invention.

In use of such close-hitch valve 20 the operating lever 20' is extended around to one side of the bowl for ready access without necessity of the user having to reach to the rear 40 of the bowl.

What is claimed is:

1. A siphon jet closet having, in combination, a bowl, flush water supply means including a control valve, and a water trap between 45 said valve and the jet passage of the bowl whereby to minimize the inert air capacity between valve and jet passage; said trap provided with a discharge port which is substantially coaxial with the intake end of the 50 jet passage; whereby to issue the flush water directly into the said end.

2. A siphon jet closet having in combination a water trap for holding water in the flush line to the jet passage of the closet and 55 thereby displace air which would otherwise be discharged into the bowl incident to passage of water to the intake of the said passage, said trap having its outlet arranged coaxially with the jet passage of the closet.

60 3. An air eliminator, for siphon jet closets, consisting of a plug device forming a trap interposed between a flush water supply means and the intake of the jet passage of the closet, and adapted to be inserted in the bowl body 65 as a unit.

4. An air eliminator, for jet passage closets, consisting of a trap interposed between a flush water supply means and the intake of the jet passage, and comprising a displacement chamber insertible bodily into the closet body and having coupling nipple at its outer end.

5. An air eliminator, for jet passage water closets, consisting of a trap interposed in the supply water line in advance of the intake mouth of the passage and provided with a discharge port which is co-axial with the mouth of the passage.

6. A siphon jet closet bowl having a flush rim around its top and a jet passage which communicates with the rim chamber, a spud connection, and a diverting dam wall intercepting all of the water coming from the spud and directing all of the water into the jet passage and being disposed at the top of the passage and wholly above the basin water level of the bowl to eliminate any obstruction thereof.
